TYPEWRITING MACHINE

Miles H. Mann, West Hartford, Conn., assignor
to Underwood Elliott Fisher Company, New
York, N. Y., a corporation of Delaware

Application December 27, 1940, Serial No. 371,939

27 Claims. (Cl. 197—126)

This invention relates to typewriting machines and more particularly to machines usually referred to as fanfold or continuous billing machines, wherein carbon sheets are supported in interleaved relation between superposed continuous webs, or the plies of a fanfolded web, and are shiftable or retractable therealong for registration with succeeding web portions or forms. Still more particularly, the invention relates to devices for retracting the carbon sheets by power mechanism.

The invention may be applied to a machine embodying the broad principles of operation disclosed in the patent to Wernery and Smith No. 1,132,055, dated March 16, 1915. In the machine shown in that patent, a platen is supported in a frame that is displaceable above the general plane of a typewriter carriage to allow the carbons to be retracted along the web plies with the latter in a straightened-out condition. Furthermore, a paper-gage is displaceable together with the platen from an out-of-way position to an effective position. While these details of construction are desirable, the invention is to be considered broadly as applicable to any billing machine wherein carbon sheets are successively registered with succeeding portions of a continuous web.

It is a main object of the invention to provide for use with such machines a power driven carbon-retracting device that is efficient and reliable in operation and adds a minimum of weight to the typewriter carriage.

It is a further object of the invention to provide a simple electric motor-driven carbon-retracting device having a reliably effective control mechanism.

It is also an object of the invention to provide a power-retracting device that is operable by a motor on the frame, so that the weight of the motor does not impede the normal movements of the carriage.

Another object of the invention is to provide a power-driven retractor which is operative in response to displacement of the platen to straighten the web, without special attention by the operator.

Still another object of the invention is to provide, in combination with a normally inactive power-driven carbon-retracting mechanism, a paper-gage which is movable from an out-of-way to an extended, effective position; and when so extended, renders the power-retracting mechanism active.

Another object of the invention is to provide

for automatic termination of the power-driven carbon-retracting operation responsive to the retraction of the carbons to a definite position.

It is also an object of the invention to provide a power drive for retracting the carbon sheets, which drive normally does not impede the movement of the carbons toward the platen.

Still another object is to incorporate in the power drive to the carbon carrier, devices to counterbalance the weight of the web hanging from the rear of the machine so that the web and the carbons advance freely during line-spacing operations, without slipping on the platen.

Other objects and features of the invention will readily be apparent upon a consideration of the detailed description which follows, as that description is read in the light of the accompanying drawings.

In the accompanying drawings:

Figure 1 is a general perspective view of a billing machine embodying the invention.

Figure 2 is a front perspective view showing the platen in a displaced position upon the carriage and also showing the manner in which an extension carrying a carbon carrier is attached to the carriage.

Figure 3 is a sectional right-hand side view showing a displaceable platen sub-frame and a latching device holding the sub-frame in normal position, the section being taken just rightwardly of the middle of the carriage.

Figure 4 is a sectional side view similar to Figure 3 taken near the right carriage end and illustrates a gage bar operable to release the latching device.

In Figure 5, the platen sub-frame of Figure 4 is shown in a fully displaced position.

Figure 6 differs from Figure 4 in that the latching device has been released by a small forward displacement of the gage bar.

Figure 7 is a sectional view similar to Figure 3 but shows the platen supporting frame partly displaced and a trip pawl thereon starting to actuate a lever for initiating a power-retraction of the carbon carrier.

Figure 8 is a fractional side view of the typewriter carriage and its extension, as viewed from the left side of the machine, including portions of the power-retracting mechanism for the carbon carrier. A web is shown as being typed upon in an advanced position.

In Figure 9, the platen frame is almost fully displaced and a gear of the retractor mechanism is shown engaged with a power-driven pinion

or gear to cause a power retraction of the carbon carrier.

Figure 10 illustrates the carbon carrier as just having been moved to a retracted position.

Figure 11 is a skeleton perspective view of a belt drive for retracting the carbon carrier, as viewed from the left rear of the machine.

Figure 12 illustrates the belt drive of Figure 11 in side elevation from the left side of the machine.

Figure 13 shows a portion of the belt drive seen in Figures 11 and 12, in rear elevation.

Figure 14 is a perspective view showing a motor and drive connections therefrom to drive the typewriter carriage and the carbon carrier retractor mechanism.

Figure 15 is a plan view showing the motor of Figure 14 and transmission parts to drive a flexible shaft.

Figure 16 shows a plan view of the rear portion of the drive mechanism for retracting the carbon carrier, together with control mechanism therefor.

Figure 17 is a rear perspective view of substantially the mechanism seen in Figure 16, in the same position.

In Figure 18, the carbon carrier retracting mechanism is shown conditioned for operation by a power-driven gear.

In Figure 19, the rearward power movement of the carbon carrier is shown as having been automatically interrupted as an incident to the retraction of the carbon carrier against a stop.

Figure 20 is a perspective view of the mechanism seen in Figure 19 but showing the retractor mechanism in the process of being disconnected from the power driven gear.

Figure 21 is a diagrammatic showing of means to energize the motor for the duration of the carbon carrier retraction.

Referring now to Figure 1, a carriage 10 is mounted to travel upon front and rear rails 11, 12 of a stationary typewriter frame generally indicated by the numeral 13. A spring motor 14 moves the carriage in letter-feed steps in response to each typing impression made by type-bars 15. The illustrated carriage 10 comprises a main frame 16, a case-shiftable frame 17 within the main carriage frame 16, and a pivotally displaceable sub-frame 18 carrying a writing support in the form of a platen 21. The frame 17 is case-shiftably mounted within the main carriage frame 16, in a manner not shown, but as is usual in Underwood billing machines, and comprises end plates 22 connected by several cross bars, one of which is indicated at 23. The displaceable subframe 18 is shown to consist of opposite end pieces 24 and a bar 25 rigidly connecting them, see Figures 2 and 3. The displaceable frame 18 is normally located within the case shift frame 17 so that the platen 21 bears upon front and rear feed rolls 26 and 27, respectively, see Figures 3 and 4. At each end of the carriage, the sub-frame is pivotally supported by means of studs 28 extending inwardly into the end pieces 24 from the case shift frame end plates 22. At the rear of the platen, the end pieces 24 of the sub-frame 18 seat normally upon collars 29 provided upon a rod 32. The rod 32 is pivoted in the opposite end plates 24 of the frame 17 and has near each of its opposite ends a latch arm 31 secured to it. Each arm 31 has a hook formation 33 that normally overlies a pin 34 on an end piece 24 of the sub-frame to hold the latter down. The hook or latch arms 31

are rearwardly swingable to clear the pins 34 and to thereby render the said sub-frame 18 displaceable to the position seen in Figures 5 and 10. A spring 35 tends to swing the arms 31 forwardly into latching position and a downwardly extending branch 36 on one of the arms 31 limits the forward motion of the latch arms by engagement with the bar 23. The platen 21 is rotatable within the displaceable sub-frame 18 by means of a spindle 37 extending through the end plates 24 of the sub-frame 18. The platen spindle 37 has at each end a gear 38 secured to it and adjacent to each gear 38 is another gear 41 secured to a stub shaft 42 which is revolvably mounted upon the adjacent case-shift frame end plate 22. As seen in Figures 1 and 2, there is provided upon each end of the carriage, another gear 43 meshing with one of each of the gears 38 and 41. Each stub shaft 42 is revolvably by a knob 44; and since each gear 43 is in mesh with a gear 38 and a gear 41, the platen 21 is revolvably by turning either one of the knobs 44.

Attached to the rear of the carriage 10 is a rectangular extension or shelf 45, formed of light-gage sheet metal and having weight-reducing openings 46. This extension is formed with downwardly-turned flanges 47 along the periphery and also along said openings 46 to stiffen it. At the forward end, the extension 45 is slidably carried for small limited lateral movements upon a rod 48 extending intermediate two spaced brackets 51 reaching rearwardly from the typewriter carriage 10. The brackets 51 are secured to the rear of the main carriage frame 16 in a manner, not shown, and the carriage extension 45, therefore, does not case-shift with the case-shift frame 17. About half way rearward of the carriage 10, the extension 45 has secured to it a downwardly reaching bracket 52 carrying a plurality of laterally spaced rollers 53 adapted to run in a stationary channel bar 54, between vertically spaced guide faces thereof. The channel bar is secured to a framework 55 extending from the rear of the typewriter frame 13 and comprising two rearwardly extending triangular plates 56, rigidly joined in slightly converging relationship, at their rear ends, by a U-shaped plate 57 and secured at their front ends to the rear portion of the typewriter frame 13. The triangular plates 56 are also rigidly joined half way between the channel bar 54 and the typewriter frame 13 by a plate 58, and in order to prevent the machine from tipping rearwardly, there are one or more props 61 extending downwardly from the plate 58 for resting on the desk or table. Each prop may comprise of a broad foot portion 62 and a stud 63 rising upwardly and being threaded into a boss provided in the plate 58. By turning the stud 63, the foot portion 62 may be adjusted to the top of the desk and a winged nut 64 may then be tightened to lock the stud.

The rod 48 at the back of the carriage 10 extends through holes 69 provided in the peripheral flanges of the carriage extension 45 and the movement of the latter upon the rod 48 is limited by collars 65 fastened upon the rod, one at each lateral side of the extension, slightly spaced therefrom. A cushion washer 66 of rubber, or the like, is interposed between each collar 65 and the extension 45. The extension 45 is carried along by the carriage by means of two springs 67, each spring having one end secured to a collar 68 fastened upon the rod 48 and having another end secured to the carriage extension 45. The springs

67 extend in opposite directions from the collar 68 and are designed to urge the extension to assume a definite position with respect to the carriage while permitting the extension 45 to lag momentarily behind the carriage during each letter-feed movement of the carriage. The typewriter carriage 10, therefore, letter feeds substantially without interference by the mass of the extension 45 and the parts carried thereby, and thus permits utmost typing speed. The collars 65 forcefully compel the carriage extension to move with the carriage during long carriage advance and long carriage return movements. At the termination of such long movements, the springs 67 cushion the arrest of the extension.

The extension 45, when detached from the machine, can easily be twisted; but, when assembled in the machine, the rollers 53 riding in the channel bar brace it and render it substantially firm, there being always at least two of the rollers 53 confined between the guide-faces of the bar 54. The extension 45 being somewhat flexible, it is not necessary to align the channel bar 54 accurately with the rails 11 and 12 of the typewriter 13.

A conventional Underwood carbon carrier unit 71 has upon the underside of a plate 72, at each lateral end thereof, a pair of grooved rollers 73 engaging the outer side-edges of parallel trackways 74 extending along the left and right border of the carriage extension 45. The unit 71 carries upon stepped left and right brackets 75, a number of blades 76 whereto carbon sheets 81 are attached in a conventional manner. As seen in Figures 1 and 8, the work web 83 is supplied upwardly from the rear of the machine, over a guide bar 77 supported at its ends by means of brackets 78 branching outwardly from the rear end of the carriage extension 45, and extends forwardly over the carriage extension 45, and downwardly around to the front of the platen 21. The case shift frame 17 supports a usual paper apron 82 and the displaceable sub-frame 18 has a paper table 84 extending tangentially from the upper front portion of the platen 21, as seen in Figures 1 and 3. A form severing knife 85 is also carried by the sub-frame 18, see Figures 8-10, inclusive. The work web 83 consists of several plies 86 and the carbon sheets 81 extend forwardly from their supporting blades 76 in interleaved relation with the plies, the leading ends of the carbon sheets being normally about $\frac{1}{2}$ inch short of the leading ends of the work plies. Figure 8, as is indicated by the type bar 15 striking the paper, shows the work web being typed upon, the leading end of the work web being shown as having been line spaced above the cutting edge of the knife 85. The carbon carrier 71 is shown advanced forwardly of a stop 88, toward the platen, and it will be evident from the description following hereinafter that this advance has been brought about partly by lowering the displaceable sub-frame 18 and partly by advancing the work web by rotating the platen.

As already has been brought out, the platen is rotatable to advance the work web 83 by means of knobs 44. The platen may be rotated in line-spacing steps in any known manner, either manually or by power. Applicant has illustrated in Figure 14 a portion of a power actuable carriage return and line-spacing mechanism that substantially corresponds to the patent to Pitman No. 1,679,741, dated August 7, 1928. In said patent, a rack 57 is slidably mounted upon a carriage for limited movement

thereupon to actuate a line-space mechanism slide 75. The rack 57 is geared to a power rotatable pinion 56, which, when power rotated, advances said rack 57 in carriage return direction, 5 first to actuate said line-space slide and thereafter to return the carriage. In Figure 14 of the present application, the rack and the pinion corresponding to the same parts shown in the said patent are numbered 91 and 92, respectively. 10 The pinion 92 has clutch teeth 93 normally disengaged from a clutch member 94 that may be continuously driven by a motor 95 through intermediate transmission members that may comprise a belt drive 96, a shaft 97 and a worm gear drive 98, see Figure 14. To effect a line-spacing and a carriage returning operation, it is merely necessary that the pinion 92 be shifted to engage its teeth 93 with the clutch member 94. This, as evident from said above-mentioned 15 Pitman patent, may occur responsive to depressing a carriage return key, or responsive to the carriage reaching a definite position in its advance.

20 The carbon sheets are shifted from time to time to register with the succeeding forms to be typed upon. This is preferably done with the web in a straightened position so that the web plies will not bind the carbons. Accordingly, whenever it is desired to shift the carbons 81 to register with a set of succeeding forms, the sub-frame 18 is first unlocked by moving the latches 31 clear of the pins 34 and thereafter swung upwardly and forwardly to raise the platen 21 above the general plane of the carriage extension 45. See Figures 2, 9, and 10. According to the embodiment of the invention shown, means are provided to do this by a single continuous motion of the operator's hand. More particularly, a bar 101 supporting an adjustable paper gage 102 is limitedly displaceable in a forward direction upon said sub-frame 18; and when so displaced, causes the latch arms 31 to be moved clear of the pins 34. Continued forward movement of the gage bar 101 displaces 25 the sub-frame 18 about its pivot studs 28. As seen in Figures 1 and 2, the gage bar 101 is fastened midways between the ends of the carriage to a pivoted shaft 103 extending to one end of the sub-frame 18, whereat the shaft 103 carries fixedly an arm 104. Brackets 105 secured to the back of the bar 25 provide pivotal supports for the shaft 103, and a torsion spring 106 urges the gage-carrying bar 101 to normally occupy a position against an abutment screw 30 107 carried by a small bracket 108 upon the back side of the bar 25. As seen in Figure 4, the arm 104 extends normally rearwardly from the shaft 103 and carries a pawl member 111. This member 111 is engageable with a pin 110 on one of the latch arms 31 to swing the latter, together with the other latch arm 31, rearwardly when the gage bar 101 is given an initial forward motion. During continued forward motion the gage bar 101 lifts the sub-frame 18 by engaging 35 the bar 25 thereon, so that finally the sub-frame comes to rest against a pad 112 upon the forward part of the main carriage frame 16. The gage bar 101 and the sub-frame 18 will then substantially be in the position illustrated in 40 Figures 5 and 10, it being noted that the gage bar may reassume its normal position with respect to the displaceable frame 18, sometime during the displacement of the latter. The distance from the edge of the knife 85 to the gage 45 102 is equal to the length of the forms used

and, to bring the carbons into register with succeeding forms, the carbons are retracted relative to the web a distance equal to a single form length. This is accomplished by advancing the work web 83 against said paper gage 102 and shifting the carbon carrier unit 71 against the stop 88. The work web 83 is preferably advanced against said gage 102 incidental to moving the gage bar forwardly to raise the sub-frame 18. To do this, the operator lightly pinches the leading end of the web plies 86 and the gage bar 101 between the thumb and index fingers and swings the gage bar 101 while also sliding the fingers therealong to advance the leading ends of the plies to the gage 102. The gage bar 101 is preferably made of angular stock so as not to unduly bend or flex while displacing the frame. Furthermore, the bar being of angular stock provides a guide channel wherealong the fingers glide in a straight line.

Power retraction of carbon carrier

Normally ineffective power retracting means are provided for said carrier 71 which means are preferably rendered effective incidental to displacing the said gage bar 101 to raise the sub-frame 18. Referring now more particularly to Figures 11 and 12 and 17 to 20, this power retracting means will now be described. The plate 72 of the carbon carrier unit 71 has secured to the underside a bracket 115 whereto a belt 116, or its equivalent, is anchored by means of a clamp 117. The belt 116 extends rearwardly from the clamp 117 onto a winding drum 118 and may also extend forwardly onto another winding drum 121. The rear winding drum 118 consists of a shallow cup 128 and a round flat disc 131, below the cup forming a brim for retaining the belt 116. Underneath the cup 128 and the disc 131, ring gear 123 and rivets 122 secure the cup, the disc and the ring gear together. The ring gear has an internal raceway 124 constituting part of a ball bearing having also a grooved inner ring 125. The inner ring fits and is clamped onto the lower end of a stud 126 extending downwardly from a horizontal arm or support 127 swingably carried for horizontal rearward movement upon the rear end of the carriage extension 45. The opposite ends of the belt 116 are oppositely attached to the front and rear drums 118 and 121. A light spiral spring 132 anchored to the stud 126 has an end secured to the inside of the cup 128 and is tensioned to revolve in clockwise direction as viewed from the top, to keep the belt extending to the carrier 71 in taut condition. This light spring, therefore, offers substantially no resistance to the advance of the carbon carrier 71 toward the platen 21. The drum 121 upon the front end of the carriage extension 45 consists also of a shallow cup and a spiral spring 133 housed within the cup is slightly stronger than the spiral spring 132 of the rear drum 118 and constantly tends to pull the belt 116 to draw the carbon carrier unit 71 forwardly. The tension of the springs 132, 133 are so proportioned and adjusted relative to each other that the weight of the web 83, trailing from the rear end of the machine, is counterbalanced and so that the friction opposing the forward movement of the carbon carrier unit is almost overcome. The web 83 can therefore be moved forwardly with almost no opposition so that it is not liable to slip upon the platen during line spacing operations. The cup or drum 121, as seen in Figure 12, is mounted

10 to revolve by means of a ball bearing 134 upon a stud 135 that is secured by a nut 136 to the underside of a bracket plate 137 screwed upon the carriage extension 45. The cup or drum 121 has a series of integral ears 138 bent upwardly from its bottom to confine the spring 133. One end of the spring 133 is anchored to the stud 135 and the other is hooked onto one of the ears 138. The tension of the spring 133 can be changed conveniently to counterbalance webs and carbon carriers of different weights, by securing the stud 135 in different rotative positions upon the bracket 137. In order that the carbon carrier unit 71 may travel to the extreme front of the carriage extension 45, the belt may extend over a guide pulley 141. As seen in Figures 11, 12, 14, 16 and 17, the position of the arm 127 upon which the rear drum 118 is carried is normally such that the teeth of the ring gear 123 are fully clear of a rearwardly adjacent gear pinion 142. The pinion 142 is carried upon a short vertical shaft 143 constituting an appendage of one end of a flexible shaft 144 contained within a flexible tubing or casing 145. The flexible shaft 144 extends downwardly and forwardly from said short shaft 143, to the rear of the typewriter frame where it ends in a horizontal shaft appendage 146 having a spiral gear 147 secured upon it. The spiral gear 147 meshes with a worm 148 rotative with the motor driven shaft 97.

30 In the preferred embodiment of the invention, the electric motor 95 runs continuously and, therefore, also the shaft 97, the worm 148, the spiral gear 147, the flexible shaft 144 and the pinion 142. The short shaft 146 carrying the spiral gear 147, see Figures 14 and 15, is revolvably supported in brackets 151 and 152 attached to a bracket support 153 that is secured to the rear of the stationary typewriter framework 13, and the end of the flexible casing 145 adjacent the short shaft 146 is clamped by a screw at 154, to a branch 155 of the bracket 152. A cover 156 secured to the bracket 152 encloses, together with the latter, the spiral gear 147 and worm 148. The vertical shaft 143 carrying the pinion 142 rotates at its upper end in a horizontal plate 157 fastened to the underside of the carriage extension 45 by studs 158, 161, 162. Near the lower end, the short shaft 143 rotates in a bushing 163 carried by a bracket 164 depending from and riveted to said plate 157. The pinion 142 is secured to the shaft 143 and is vertically confined between the bushing 163 and the plate 157. Just below the vertical shaft 143 the flexible shaft casing 145 extends into a vertical collar 165 and is clamped thereto by a screw 166. The collar 165 is suspended from the bushing 163 as at 167 in roller bearing fashion and is free to turn thereon. Consequently, the rear end of the casing 145 is free to turn during the movement of the carriage 10, so that all drag which would otherwise result from the twisting of the casing 145, is completely avoided. It is to be noted that the flexible shaft 144 and its casing 145 are of sufficient length to allow free movement of the typewriter carriage 10 and its extension 45.

70 The arm or support 127 upon which the drum 118 is mounted is fixed upon a stud 168 depending downwardly from the carriage extension 45. A horizontally pivoted member 171 and a short link 172 preferably carried thereby, constitute a latch device to hold normally the drum carrying arm 127 against the tension of a spring 173 in its normal position seen in Figures 16 and 17.

The member 171 is pivoted at 174 to a forwardly extending part of the bracket plate 157 and has a branch ending in an upwardly extending ear 175 which, as shown in Figure 17, normally engages the plate 157 under the combined tension of the springs 173 and 197. The link 172 has a saddle 176 formed by a fork against which a pin 177 on the drum carrying arm 127 normally bears and, as seen in Figure 16, the pin 177 and the pivotal point of the link 172 lie normally in a straight line that passes forwardly of the machine, just leftwardly of the pivot 174. It follows, therefore, that the arm or support 127 being urged rearwardly by the spring 173, has the tendency to move the member 171 clockwise about its pivot 174, so that the ear 175 of the member 171 normally bears against the bracket plate 157, and causes the drum carrying arm 127 to be locked against rearward movement, see Figure 17.

The member 171 is movable about its pivot 174 to the position seen in Figure 18, in order to release the drum carrying arm 127 for rearward movement by the spring 173 to engage the ring gear 123 with the motor-driven pinion 142. Consequently, the drum 118 will be rotated and the carbon carrier 71 drawn rearwardly by the belt 116. According to the preferred form of applicant's invention, as pointed out previously, the carbon carrier 71 is retracted incidental to elevating the platen carrying sub-frame 18 to the Figure 5 position. To this end the member 171 is operable through a train of mechanism actuatable by a trip pawl 178 provided on an adjustably fixed arm 181 on the platen carrying sub-frame 18. Said pawl 178 comes into contact with a pin 182 on a lever 183 during the elevation of the sub-frame 18, when the latter approaches its fully elevated position, see Figure 7. Full movement of the sub-frame 18 to the elevated position seen in Figure 5 causes the lever 183 to be actuated. The movement given to the lever is transmitted by a rearwardly extending link 184 to a bell crank 185 on the bracket 51, and from there over a rightwardly extending link 186 to another bell crank 187 connected by a link 188 to the member 171. The bell crank 187 is pivoted upon a support 191 that is fixedly carried by the rod 48 by means of the collar 68 and another collar 192. The connecting link 188 extends rearwardly from the point where it is linked to the bell crank 187 in parallelism with the carriage extension 45 and therefore swings idly about said point whenever the carriage extension moves upon the rod 48 relatively to the carriage 10. In other words, the connecting link 188 in no way impedes the movement of the extension or shelf 45 on the carriage. The pawl 178 actuates said train only momentarily, as it is desired that the member 171 be restorable immediately after actuation independently of restoring the platen sub-frame 18. The pawl 178 for this purpose is arranged to glide off the pin 182 just prior to completing the displacement of the sub-frame 18. This is viewed in Figure 5. The arm 181 fulcrums about one of the pivot studs 28 of the sub-frame 18, but the position in which the arm travels with the sub-frame 18 depends on the position in which it is clamped thereto by a screw 193, best seen in Figure 2. The pawl 178 is pivotally carried by the arm 181 to by-pass the pin 182 on lever 183 when the sub-frame 18 is restored to normal position. In actuating the lever 183, a thin tail extending from 75

the pawl 178 reacts against a boss upon which the stud 28 is secured to the shift frame 11.

The drum 118 revolves after the ring gear 123 has swung into mesh with the pinion or gear 142 and draws the belt 116 rearwardly by winding it. Consequently, also the carbon carrier 71 is drawn rearwardly. While this occurs, the operator holds the leading end of the web stationary, as seen in Figure 10. When subsequently, due to the resulting retraction of the carbon carrier 71, the leading ends of the carbons 81 reach a position rearwardly of the knife 85, the carbon carrier 71 engages the stop 88. The stop 88 is adjustable along a serrated bar 194 extending along the full depth of the carriage extension 45. For a purpose to be later described, the bar 194 may be mounted for a limited rearward displacement, by providing the ends thereof with slots 195 and passing mounting screws 196 therethrough into the extension 45. The rearwardly movable carbon carrier 71 is therefore eventually arrested by the stop 88, and the momentarily still-power-driven drum 118 thereafter, instead of drawing the carbon carrier 71 rearwardly, draws the arm or support 127 forwardly against the tension of the spring 173 to separate the gears 123, 142. The momentum of the drum 118 and the gear 123 is sufficient to cause the arm 127 to be drawn forwardly by the belt until, as illustrated in Figure 19, the gear 123 is fully separated from the driver pinion 142, that is, until the drive to the drum is fully open. The pivoted latching member 171 and the short link 172 carried thereby concomitantly move under the tension of a spring 197 to lock the arm 127 in the forwardly moved position seen in Figure 19. It might, therefore, be said that displacement of the gage 102 and sub-frame 18 causes the power retracting means to be effective pending retraction of the carrier to a definite position, the definite position being established by the stop 88.

It should be noted that as the member 171 and the link 172 move from their Figure 18 positions to their Figure 19 positions, the spring 197 becomes effective to favor movement of the arm 127 forwardly. The power that the spring 197 is finally able to exert upon the arm 127 is greater than that of spring 173. After the power displacement of the carbon carrier has been completed, the operator may proceed to lower the sub-frame 18 to normal position, the operator still pinching the leading end of the web 83 against the paper gage bar 101. During this procedure the trip pawl 178 passes idly over the pin 182 and the latch arms 31 reengage the pins 34 on the sub-frame 18. Furthermore, also the pawl member 171 assumes normal position by swinging under the pin 112 under the influence of a spring 198. Subsequently, the leading sets of forms is torn off against the knife 85, and the succeeding set of forms may then be typed upon.

The above-described mechanism controlling the position of the arm or support 127 may be supplemented by a device for retaining the gear 123 engaged with the pinion 142, interim with displacing the carbon carrier rearwardly by power. More particularly, a pivoted latch 201 is provided having an ear 202 normally idly bearing against an off-set portion 203 of the drum-carrying arm 127, as seen in Figure 16. A hook 204 formed on a bracket member 205 is fastened to the stop bar 194 and transmits the tension of a spring 206 to urge the latch 201 counterclockwise as viewed from the top of the machine.

When, therefore, responsive to the displacement of the sub-frame 18, the arm 127 is moved rearwardly to engage the gear 123 with the pinion 142, the latch 201 moves into position to hold by its ear 202 the arm 127 against forward displacement. This assures positive engagement of the gear 123 and the pinion 142 pending full retraction of the carbon carrier 71 resulting in a rearward movement of the stop bar 194. A protuberance 207 on the bracket element 205 then engages a cam face 208 on the pivoted retaining member 201 to swing it and force its ear 202 away from the off-set 203, wherefore the arm 127 may then swing forwardly by momentarily continued rotation of the drum 118, to disengage the gear 123 from the pinion 142.

Another latch arm 211, by engaging the aforesaid ear 175, as shown in Figure 18, retains the element 171, following its operation, in operated position. This is desirable to give the arm 127 ample opportunity to swing rearwardly to engage the gear 123 with the pinion 142, it being remembered that as far as the trip pawl 178 is concerned, the member 171 is free to return to normal position after the sub-frame is completely displaced. The latch arm 211 is under constant tension of a spring 212 and the member 171 is free to move from the Figure 18 position to the Figure 19 position when the carbon carrier, in its rearward movement, has displaced the gage bar 124. The member 171 is freed from the latch 211 through a shoulder 213 on the bracket member 205 which moves the latch arm 211 free of the ear 175.

The motor 95, instead of running continuously, may normally be deenergized. This has been diagrammatically illustrated in the modification shown in Figure 21. In said figure, it can be seen that the motor circuit 214 may be closed and opened respectively by rearward and forward movements of the drum-carrying arm 127 through the provision of contact fingers 215, 216.

A motor switch 218 may also be provided to energize the motor for carriage-return operations. This switch is, of course, only necessary if the motor is to run intermittently for carbon retracting operations and carriage-return operations. The control device for the said switch 218 may be the same as illustrated in the said patent to Pitman, that is, the switch 218 may be closed under the control of the carriage-return key or the movement of the carriage to line-end position, and may be opened automatically upon arrival of the carriage in a definite return position.

What is claimed is:

1. In a writing machine having a platen supporting carriage movable on a frame in letter-feed and return directions to different positions, and a carbon carrier on the carriage movable toward and retractable from said platen; normally ineffective power retracting means for said carbon carrier, including, a motor on the frame, a retractor drive on said carriage, and means to transmit motion from said motor to said retractor drive in any position of said carriage; and means operable to render said power retracting means effective pending retraction of said carrier to a definite position.

2. In a writing machine having a platen supporting carriage movable on a frame in letter-feed and return directions to different positions, and a carbon carrier on the carriage movable toward and retractable from said platen; normally ineffective power retracting means for said carbon carrier, including, a motor on the frame,

a retractor drive on said carriage, and means to transmit motion from said motor to said retractor drive in any position of said carriage; and means on the carriage operable to render said power retracting means effective pending retraction of said carrier to a definite position.

3. In a writing machine having a platen supporting carriage movable on a frame in letter-feed and return directions to different positions, and a carbon carrier on the carriage movable toward and retractable from said platen; normally ineffective conditioned power retracting means for said carbon carrier, including, a stationarily located motor, a retractor drive on said carriage, and flexible shaft means to transmit motion from said motor to said retractor drive in any position of said carriage; and means operable to condition said power retracting means to retract said carrier.

4. In a writing machine having a carbon carrier adapted to be advanced toward and retracted from a writing support, stop means engageable by said carrier in being retracted, power means, retractor means for said carrier normally uninfluenced by said power means, but adapted to be influenced thereby to retract said carrier from said support, and means operable to cause said retractor means to be influenced by said power means to retract said carrier, said last means including provision to render said retractor means uninfluenced by said power means responsive to retraction of said carrier against said stop means.

5. In a writing machine having a platen supporting carriage movable on a frame; a carbon carrier on said carriage adapted to be advanced toward and retracted from said platen; continually operating power means, a belt drive, on said carriage, including a belt connected to the carbon carrier and a drum normally disconnected from said power means but operable thereby to drive said belt to retract said carbon carrier, and means operable to connect said drum with said power means pending retracting of the carrier to a definite position.

6. In a writing machine having a platen supporting carriage movable on a frame, and having a carbon carrier on the carriage movable toward and retractable from the platen, normally ineffectuate power retracting means for said carrier, a limitedly movable element extending parallelly along the moving path of said carrier, a stop adjustable along said movable element and engageable by said carrier in being retracted, to displace said movable element, and means conditionable to effectuate and ineffectuate said power retracting means, being conditionable to ineffectuate said power retracting means responsive to displacement of said movable element by said carrier.

7. In a writing machine having a carbon carrier adapted to be advanced toward and retracted from a writing support, a belt drive associated with said carrier and adapted to be driven to retract the latter, means normally urging said belt drive to advance said carrier, normally ineffective power means adapted to drive said belt drive to retract said carrier, and means to render said power means effective pending retraction of the carrier to a definite position.

8. In a writing machine having a carbon carrier advanceable toward and retractable from a writing support; drive means operable to retract said carrier; said drive means including a belt attached to said carrier and a drum adapted by winding the belt to retract said carrier, a light

spring associated with said drum to keep said belt taut, said spring offering substantially no resistance to the advance of said carrier, normally ineffective power means adapted to turn said drum to cause it to retract said carrier, and means conditionable at will to render said power means effective to turn said drum to thereby wind said belt and retract said carbon carrier.

9. In a writing machine having a carbon carrier advanceable toward and retractable from a writing support; drive means operable to retract said carrier, said drive means including a belt attached to said carrier and a drum adapted by winding the belt to retract said carrier, a spring associated with said drum tending to wind said belt and retract said carrier in order to keep said belt taut, spring means associated with said carrier to at least counterbalance the tendency of said spring to retract said carrier, normally ineffective power means adapted to turn said drum to cause said belt to retract said carrier, and means conditionable at will to render said power means effective to retract said carrier.

10. In a writing machine having a carbon carrier adapted to be advanced toward and retracted from a writing support, a belt drive for said carrier, comprising, two drums, one spaced from the other in the direction in which the carrier is advanceable and retractable, a belt extending intermediate said drums, said drums having each an opposite end of said belt attached and wound thereupon, means operatively connecting said belt intermediate said drums to said carrier, a spring associated with each one of said drums to keep the belt taut intermediate said drums, said springs being relatively proportioned so that the carrier has a tendency to advance toward the writing support, normally ineffective power means adapted to drive said belt drive to retract said carrier, and means to render said power means effective pending retraction of said carrier to a definite position.

11. In a writing machine having a writing support and a carbon carrier movable toward and retractable from the writing support; a motor; a belt drive for retracting said carrier, including a belt operatively connected with said carrier and a drive drum for said belt rotatable in one direction to retract said carrier; means for rotating said drum in the said one direction by said motor, including a drive connection adapted to be opened and closed; a member movable to open and close said connection; means influencing said member to close said connection; means for holding said member responsive to being moved to open said connection; means operable for causing said drum to be driven by said motor to retract said carrier, including means operable to effect a release of said member by said holding means for causing closure of said connection; and means engageable by said carrier in being retracted to cause said member to be moved to open said drive connection.

12. In a writing machine having a writing support and a carbon carrier movable toward and retractable from the writing support; a belt drive for retracting said carrier, including a belt operatively associated with said carrier and a drive drum for said belt rotatable in one direction to retract said carrier; power means for driving said drum in the said direction, including a drive connection adapted to be opened and closed; means including a member movable to close and open said connection; a spring influencing said last means to close said connection; means for

holding said member responsive to being moved to open said connection; means operable for causing said power means to drive said drum to retract said carrier, including means operable to effect a release of said member by said holding means for causing closure of said connection under the influence of said spring; and means engageable by said carrier in being retracted to cause said member to be moved to open said drive connection.

13. In a writing machine having a writing support and a carbon carrier movable toward and retractable from the writing support; stop means against which said carrier is retractable; a belt drive for retracting said carrier, including a belt operatively connected with said carrier, and a drive drum for said belt rotatable in one direction to retract said carrier; a gear on said drum; power means; a gear adapted to be driven by said power means to rotate said first gear for retracting said carrier; a support for said drum and said first gear movable to engage or disengage said gears; means influencing said support to engage said gears; means for holding said support responsive to being moved to disengage said gears, and means operable for causing said first gear to be driven to retract said carrier; including means operable to effect a release of said support by said holding means to cause said gears to engage; said influencing means being of such strength and said second gear and said support being so arranged that said support is movable to separate said gears by momentarily continued rotation of said drum subsequent to power retraction of said carrier against said stop means.

14. In a writing machine having a writing support and a carbon carrier movable toward and retractable from the writing support; stop means against which said carrier is retractable, a belt drive for retracting said carrier, including a belt operatively connected to said carrier, and a drum rotatable to drive said belt to retract said carrier, a gear on said drum, a power drive gear, a support for said first gear movable to engage and disengage said first gear and said power drive gear, means influencing said support to engage said gears, a spring, means operated by said spring to hold said support responsive to being moved to disengage said gears, and means operable for causing said first gear to be driven by the power drive gear to retract said carrier, including means operable to release said support from said holding means for engagement of said gears, said influencing means being of such strength and said second gear and said support being so arranged that said support is movable to separate said gears by momentarily continued rotation of said drum, subsequent to power retraction of said carrier against said stop means, and said spring operated means being designed to favor movement of said support to separate said gears after an initial movement of said support to separate said gears.

15. In a writing machine having a writing support and a carbon carrier movable toward and retractable from the writing support; a belt drive for retracting said carrier, including a belt operatively connected to said carrier, and a drive drum for said belt rotatable in one direction to retract said carrier; a gear on said drum; power means; a second gear adapted to be driven by said power means to rotate said first gear for retracting said carrier; a support for said drum and said first gear movable to and from a normal

position to respectively disengage and engage said gears; latch means automatically effective to hold said support when moved to engage said gears; manually operable means for causing said support to move to engage said gears; and means limitedly movable by the retraction of said carrier to a definite position to release said latch means and stop said carrier; said second gear and said support being so arranged that said support is movable to separate said gears by a momentarily continued rotation of said drum subsequent to the release of said latch means by said limitedly movable means.

16. In a writing machine having a platen supporting carriage movable on a frame in letter-feed and return directions to different positions, and a carbon carrier on the carriage movable toward said platen; normally ineffective power retracting means for said carrier, including, a 15 stationarily located motor, and means to transmit motion from said motor to said carrier in any position of said carriage; and means operable to render said power retracting means effective pending retraction of said carrier to definite position.

17. In a writing machine having a carriage movable on a frame in letter-feed and return directions to different positions, a platen displaceable on said carriage, and a carbon carrier on said carriage movable toward the platen; normally ineffective power retracting means for said carrier, including a stationarily located electric motor, a retractor drive on the carriage, and means to transmit motion from said motor to said retractor drive in any position of the carriage; and means operative upon displacement of the platen to render said retracting means effective, and operative upon retraction of the carrier to a certain position to render said retracting means automatically ineffective.

18. In a writing machine having a carriage movable on a frame in letter-feed and return directions, a platen displaceable on said carriage, and a carbon carrier on said carriage movable toward the platen; an electric motor on the frame; normally ineffective motor-operable means adapted to retract said carrier in any position of the carriage; and means operative upon displacement of said platen from writing position, to render said motor operable means effective and automatically operative upon retraction of the carrier to a certain position to render said motor operable means ineffective to exert driving influence upon the carrier.

19. In a writing machine having a carriage movable on a frame in letter-feed and return directions, a platen on said carriage, and a carbon carrier on said carriage movable toward the platen; an electric motor on the frame; normally ineffective motor-operable means adapted to retract said carrier in any position of the carriage; control means on the carriage, and means, conditionable by said control means to render said motor-operable means effective, said conditionable means including a provision to render said motor-operable means ineffective to exert driving influence upon the carrier responsive to the retraction of the carrier to a certain position.

20. In a writing machine having a carriage movable on a frame in letter-feed and return directions to different positions, a platen on said carriage, and a carbon carrier on said carriage movable toward the platen; a stationarily located electric motor; normally ineffective motor- 70

operable means adapted to retract said carrier in any position of the carriage, including a normally open clutch; and means to close and open said clutch, including means operative upon retraction of the carrier to a certain position, to open said clutch.

21. In a writing machine having a carriage movable on a frame in letter-feed and return directions to different positions, a platen on said carriage, and a carbon carrier on said carriage movable toward the platen; a stationarily located electric motor; normally ineffective motor-operable means adapted to retract said carrier in any position of the carriage, including a normally open drive connection, and means to open and close said drive connection, including, means engageable by said carrier in being retracted, and means responding to the engagement of said engageable means by said carrier, to open said drive connection.

22. In a writing machine having a carriage movable on a frame in letter-feed and return directions, a platen displaceable on said carriage and a carbon carrier on said carriage movable toward the platen; an electric motor on the frame, normally ineffective motor-operable means adapted to retract said carrier in any position of the carriage, including a normally open clutch; means, operative upon displacement of said platen, to engage said clutch, to render said motor-operable means effective; and means, operative upon retraction of the carrier to a certain position, to cause clutch disengagement.

23. In a writing machine having a carriage movable on a frame in letter-feed and return directions to different positions, a platen on said carriage, and a carbon carrier on said carriage movable toward the platen; a normally deenergized carriage return motor on the frame; means operable by said motor to retract said carrier in any position of the carriage, including a normally open drive connection; and means to close said drive connection and energize said motor, including a provision to deenergize the motor and open said drive connection automatically responsive to the retraction of said carrier to a certain position.

24. In a writing machine having a carriage movable on a frame in letter-feed and return directions, and a platen on said carriage, relative to which carbon sheets on the carriage are advanceable and retractable; normally ineffective power retracting means for said carbons, including a stationarily located electric motor, and means operable by said motor to retract said carbons in any position of the carriage; and means to render said power retracting means effective.

25. In a writing machine having a carriage movable on a frame in letter-feed and return directions, a platen on said carriage, and a carbon carrier on said carriage movable toward the platen; an electric motor on the frame; normally ineffective motor-operable means adapted to retract said carrier in any position of the carriage; control means; and means, conditionable by said control means to render said motor-operable means effective, said conditionable means including a provision to render said motor-operable means ineffective to exert driving influence upon the carrier responsive to the retraction of the carrier to a certain position.

26. In a writing machine having a writing support relatively to which carbon sheets are retractable to a certain position; motor-drive

means to retract said carbon sheets, including a drive connection adapted to be closed and opened respectively to render said motor-drive means effective or ineffective; an operable control; and means adapted, by the operation of said control, to render said drive connection closed, and adapted, incidental to the restoration of the carbon sheets to the said position, to render said drive connection automatically open, said last means including a provision whereby the drive connection is rendered open irrespective of when the control is restored after operation.

27. In a writing machine having a displaceable platen relatively to which carbon sheets are

retractable to a certain position; motor-drive means to retract said carbon sheets, including a drive connection adapted to be closed or opened respectively to render the motor-drive means effective or ineffective; and means adapted, incidental to the displacement of the platen, to render said drive connection closed, and adapted, incidental to the retraction of the carbon sheets to the said position, to render said drive connection open, said last means including a provision whereby the drive connection is rendered open irrespective of when the platen is restored after displacement.

MILES H. MANN.
